GUNJI ISONO, OF HAMADERA-CHO, SENHOKU-GUN, OSAKA, JAPAN

TRACK BUMPER

Application filed December 11, 1928, Serial No. 325,207, and in Japan January 7, 1928.

This invention relates to track bumpers to be provided at the dead end of a railway track.

One of the objects of the invention is to provide a track bumper which will stop an oncoming car or a train of cars, not in an instantaneous manner, but after a short braking distance, thus avoiding any serious injuries either to the cars or to the bumper itself.

Another object of the invention is to so design the bumper as to cause the brake shoes to press uniformly against the rails when the bumper is acted upon.

With these objects in view, the invention consists of an impact block, a pair of front brake shoes contacting with the track rails, or with rails specially provided for that purpose, at the bottom face of the top flange 20 or tread of the rails and also at the web thereof, and a pair of rear brake shoes contacting with the rails at the top face of the tread, front and rear leg members connecting the respective shoes with the impact block, a resilient means to press the front brake shoes laterally against the rails and a cam means, such as, for example, an inclined shoulder provided on one set or pair of shoes and a pin or the like serving as 30 a roller operating between the two sets in such a manner that one set can be displaced longitudinally with respect to the other with a minimum friction, so that both sets of shoes are brought closer together when the 35 bumper device is acted upon.

When a car collides with the track bumper, a pull exerted on the front leg members, a push exerted on the rear leg members and the corresponding forces exerted on the respective shoes as produced by the operation 40 of cam means, in co-operation with the forces exerted by the resilient means, cause the shoes to uniformly press upon the rails, creating sufficient friction to stop run-away cars within a certain short and pre-determined distance.

Referring to the accompanying drawings. Figure 1 is a side view of a bumper device according to my invention.

Figure 2 is a front view thereof.

Figure 3 is a fragmental side view, on an enlarged scale, of the rear portion of the device.

Figure 4 is a horizontal section on line 4-4 of Fig. 3.

Figure 5 is a vertical section on line 5-5 of Figure 3.

Figure 6 is a vertical section on line 6-6 of Figure 3.

Figure 7 is a fragmental side view of the front portion of the device.

Figure 8 is a horizontal section on line 8-8 of Figure 7.

Figure 9 is a vertical section on line 9-9 of Figure 7.

Figure 10 is a side view of the lower portion of the front leg member of the device.

Figure 11 is a bottom end view thereof.

Figure 12 is a detail side view of the device, partly broken away, showing rear 70 cam means operating between the front and the rear brake shoes.

Figure 13 is a section on line 13-13 of Figure 12 looking in the direction of the arrows.

Figure 14 is a vertical section on line 14-14 of Figure 12.

Figure 15 is a central section, on an enlarged scale, of the device, with the leg members removed, showing in detail spring 80 means to exert a lateral pressure on the front brake shoes.

Figure 16 is a horizontal section on line 16-16 of Figure 15.

Figure 17 is a vertical section on line 85 17-17 of Figure 15.

Figure 18 is a vertical section on line 18-18 of Figure 15, showing the distance piece disposed between the inner front shoes.

Referring now more particularly to the accompanying drawings, 1, 1 are the track rails. Between these rails and constituting the stationary part of the device are two auxiliary rails 2, 2 of I-section. Slidably mounted on each of the auxiliary rails are 95

pairs of front brake shoes 3, 3 and rear brake shoes 4, 4. Pivotedly and loosely connected, as by pin 5 and elongated aperture 6, to the front shoes and at the front end thereof, is a pair of front leg members 7, 7 fastened to 100

gether by means of a tie 8; pivotally connected in ordinary manner to the rear brake shoes by means of a pin 9, at the rear end thereof, is a pair of rear leg members 10, 10 fastened together by a tie 11. The front and rear leg members form a triangle, beyond the apex of which the rear members extend slightly; and on the free ends of said rear members an impact block 12 is mounted with its re-inforcing webs 13 embracing the aforesaid free ends. The front leg members, the rear leg members and the impact block are secured together by a pin at the apex of the triangle.

15 The front brake shoes 3 are substantially of L-section, each consisting of a horizontal flange portion or foot 14 and a vertical web portion 15 (Fig. 15); the flange portion 14 contacting at its tip end with the web of the auxiliary or brake rail 2, and at its upper face with the under side of the top flange or tread of the rail.

20 The rear brake shoe 4 is disposed intermediately of a pair of front brake shoes 3 and flatly presses upon the upper surface of the top flange or tread of the auxiliary rail.

25 The rear portions of the front shoes and the front portions of the rear shoes lie in juxtaposition, the latter being interposed between the former. The front and the rear shoes are formed with elongated, backwardly and downwardly sloping apertures 16, 16' and 17, 17' to register each other, through which extend pins or rollers 18, 19 respectively. Preferably the front shoes may be provided with inwardly projecting flanges 20, 21 at these points, with sloping shoulders 22, 23 bordering on the respective apertures. When the rear shoes are pushed backwardly 30 relatively to the front shoes, as hereinafter more fully described, the pins 18 and 19 rolling along the inclined edges of the apertures serve to guide the relative motion with a minimum of friction.

45 Disposed at the front portion of the front shoes and mounted on the pin 5 is a transmission bar 24 abutting at its free end against the forward end of the rear shoe.

50 At the middle portion of the device, there is a pair of levers 25, 25, substantially of channel section, which press inwardly the unit or assemblage consisting of two pairs of front shoes, auxiliary brake rails interposed therebetween, and a distance piece 26, 55 all held together by means of a bolt 27 and a nut 28. The apertures formed in the rear shoes for the bolt 27 to extend through are elongated, as at 29 (Fig. 17), to allow a longitudinal movement of the rear shoes relative 60 to the front shoes. Between the upper ends of the levers 25, there are interposed compression springs 30, 31, arranged in a casing 32, which is mounted on a guide shaft 33. These springs exert an outward pressure in 65 opposite directions against the levers, as in-

dicated by the arrows 34, thus forcing the right-hand lever to move towards the right, and the left-hand lever toward the left through the intermediary of a sleeve 35 slidably mounted on the guide shaft. These outward pressures are transmitted to the group of shoes as inwardly-directed compressive forces, as shown by the arrows 36, owing to the presence of the head of the bolt 27 and the nut 28. The auxiliary rails 2 are somewhat loosely mounted upon the sleepers, so that they can move slightly in lateral directions, and in this way, the compression is transmitted to the elements lying between the two levers.

70 The above mentioned spring means provides a friction of a suitable magnitude against the sliding motion of the front brake shoes to bring about the effective operation of cam means including the rollers 18, 19 inducing a proper gripping or biting action of the shoes on the brake rails 2. Besides, it serves to uniformly distribute the upward pressure of the front shoes 3 acting against the lower surfaces of the treads of the brake rails, owing to the pressure exerted on the lowermost edges of the flanges or feet 14 of said shoes.

75 The operation is as follows:—

80 When a car collides with the impact block 12 of the track bumper in the direction indicated by the arrow 37 in Fig. 1, the force of collision will be divided into a pull on the front leg members 7 and a push on the rear leg members 10. The pull on the front leg members may again be decomposed into a vertically—and upwardly—directed component and a horizontally—and rearwardly—directed component. The former tends to lift the front shoes, thereby pressing their feet 14 against the underside of the treads of the auxiliary rails, and thus serves to increase the surface friction.

85 The push on the rear leg members may also be decomposed into a vertically—and downwardly—directed component and a horizontally—and rearwardly—directed component. The vertical component acts to press the rear shoes 4 upon the top surface of the auxiliary rails and increases the friction, while the horizontal component, in co-operation with the horizontal component as transmitted through the intermediary of the transmission bar 24, drives the rear shoes 4 rearward relatively to the front shoes, as made possible by the elongation of the apertures pertaining to the pins or rollers 18, 19. In this relative movement of the rear shoes with respect to the front shoes, as guided by the rollers 18, 19 extending through the respective inclined apertures formed in the brake shoes, the shoes are brought vertically closer together against the rails, and the friction is further increased. The slope of the apertures should be so proportioned in relation to the inclination of the 90

leg members that the resulting vertical pressures on the rails are uniform along the lengths of the shoes.

The device, as a whole, is driven back a certain distance by the force of the collision, until the kinetic energy of the colliding body has been expended by the initial side friction due to the springs and the increased friction between the brake shoes and the auxiliary 10 brake rails.

After the device has thus been operated, the compression springs 30, 31 are loosened by unscrewing the nut on the guide shaft 33, the device is brought back to its initial position 15 and the springs again restored to their normal compressed state, to be ready for another emergency.

What I claim is:

1. A track bumper comprising an impact 20 block, a shoe contacting upwardly with a rail, another shoe contacting downwardly with the rail, and two leg members pivotally connecting the respective shoes with the said impact block, means to press one of the shoes 25 upon the rail to exert an initial friction thereon, the said shoes being displaceable with respect to each other, and cam means on the shoes to bring them closer together when a force of collision tends to separate them in 30 longitudinal direction.

2. A track bumper comprising an impact block, a shoe contacting upwardly with a rail and pressed to the rail from a side thereof, another shoe contacting downwardly with 35 the rail, said shoes having inclined apertures formed therein, two leg members pivotally connecting the respective shoes with the said impact block, a roller extending through the inclined apertures in the shoes, and means to 40 press one of the shoes laterally against the rail.

3. A track bumper comprising an impact block, a shoe contacting upwardly with a rail and pressed to the rail from a side thereof, 45 another shoe contacting downwardly with the rail, said shoes being formed with registering inclined apertures, two leg members of substantially equal lengths pivotally connecting the outer ends of the respective shoes 50 with the said impact block, a roller extending through the said apertures, and spring means to normally press the first-mentioned shoe against the rail.

In testimony whereof I affix my signature.
